UNITED STATES PATENT OFFICE.

MARTIN VERBEYST, OF PARK RIDGE, NEW JERSEY.

AMUSEMENT GAME.

Application filed October 26, 1923. Serial No. 670,908.

To all whom it may concern:

Be it known that I, MARTIN VERBEYST, a citizen of the United States, and a resident of the borough of Park Ridge, county of Bergen, State of New Jersey, have invented an Improvement in an Amusement Game, of which the following is a specification. This invention relates to amusements and more particularly to amusement games founded upon the principle of the well known game of baseball.

It is an object of the invention that of providing a novel amusement device which is founded upon the principle of the national game of baseball, which shall require a certain degree of skill and accuracy, acquired only by pitching baseballs for its playing, and which shall afford the players the physical exercise enjoyed in playing baseball games, and give the players the pleasures derived from such games.

It is another object of the invention that of providing a clean and harmless amusement device which is simple in construction and not likely to get out of order or operation, which is representative of a baseball player in the act of swinging a bat, which is attractive and interesting in that it requires a certain degree of skill and accuracy on the part of the player to score any hits against the device, and which indicates positively the hits scored by the pitched balls against the device in terms of bases of a baseball diamond.

It is still another object of the invention that of providing an amusement device which stimulates and encourages the clean and healthy game of baseball, which shall afford the players the means to practice in the accuracy of pitching balls, and the means to indicate the accuracy with which the hits are scored in terms of bases of a baseball diamond.

Other objects of the invention, together with its advantages and distinguishing features, shall appear as the specification proceeds, which specification is only descriptive of the accompanying drawings forming a part thereof. It is understood that the said drawings are only illustrative of one embodiment of the invention to which I do not limit myself, since the invention can be de-

veloped into various forms without in the least departing from its spirit and scope.

Referring to the drawing herein in which I have illustrated the aforementioned illustrative embodiment of the invention:

Figure 1 illustrates one embodiment of the invention and shows the figure of a baseball player holding a bat, and an indicating board illustrating a miniature baseball diamond;

Figure 2 illustrates diagrammatically the electrical circuit connecting the electrical mechanism carried by the bat with the indicating means and the indicating board;

Figure 3 shows the rear of the player's figure and the mechanism with which it is provided for moving its arms and hands, and the bat which it carries;

Figure 4 shows a modified form of the construction shown in Figure 3, wherein the arm and bat actuating mechanism is constructed and arranged so as to render the device more compact;

Figure 5 is a fragmentary view of the player's figure showing the connection of the bat with the moving arm of the figure and the manner in which the bat is supported on the figure;

Figure 6 shows an end portion of the bat in its rearmost position and the buffer plate against which the bat abuts on its rearward movement;

Figure 7 shows also an end portion of the bat in its forward position with one of its base plugs or circuit closers moved inwardly by a pitched ball;

Figures 8 and 9 illustrate more in detail the position of one of the base plugs or circuit closers before and after being hit by a pitched ball;

Figure 10 is a sectional view taken on line 10-10 in Figure 11 and illustrating the normal position of the base plugs;

Figure 11 is a side view of the end portion of the bat looking toward the heads of the base plugs; and

Figure 12 is a rear view of the end portion of the bat showing the electrical plates 100 and contacts by means of which the circuits to the indicating means on the miniature diamond are closed when any of the base plugs are actuated by a pitched ball.

Figure 13 shows the hinged member connecting the moving arm of the figure to the bat proper.

The device constructed within the scope of my present invention finds special adaption in amusement parks or arcades, carnivals, picnics, or circuses; and also in training quarters of baseball players and athletic institutions. The device being based upon the national game of baseball provides a clean, healthy and interesting amusement, and those that play it can, aside from the brisky physical exercise which they get, develop a good degree of skill and accuracy in the art of pitching balls. The device in addition to being amusing is meant to provide the means for a physical exercise and the means for developing a certain degree of skill in pitching baseballs.

Referring to the drawings, the human figure 20 represents a baseball player in the act of swinging a bat 21, which bat is held in the hands 22 and 23 of the figure 20. The hand 22 consists of a glove 25, which is merely used to cover the bat 21 at the place where it is pivoted. The hand 23 also consists of a glove which covers the connection of the bat with the arm 26, the said arms being hinged as at 27 at the shoulder of the figure. The means for pivoting the bat 21 to the figure are the following: A bar 30, secured to the body of the figure 20, by means of bolts or rivets 31, and a section of a ring 32 which is secured in any approved manner to the outer end of said bar 30. With the section of ring 32 cooperates a second section of a ring 33 which is held on the first ring section 32 by means of bolts 34 and 35. The bat 21 is clamped in place by means of these cooperating sectional rings 32 and 33, and the bolts 34 and 35 which hold the sectional sections together. The bar 30 is provided with a socket 38 and the sectional ring 32 is provided with a stub 39 which fits in said socket 38; and by means of this arrangement the bat 21 is permitted to swing on its longitudinal plane. It is understood that any other approved method may be resorted to for pivoting the bat, the means just described being only illustrative of an embodiment. To the body of the figure 20 is also secured a buffer plate 40 by means of a cross rod 41, and at its lower end to the bar 30. This buffer plate 40 is fast secured to the body and acts as a stopper for the bat 21 on its rearward movement. Another purpose of the provision of this buffer plate 40 will be described hereafter.

The bat 21 adjacent its lower or grip end is formed with a hole 45 through which passes a stub 46 carried by the arm 26. Surrounding the stub 46, between the bat 21 and the arm 26, is a spring 47 which acts as a cushion for the bat 21. A spring 49 is employed to urge the bat in its forward posi-

tion as shown in Fig. 5, and this spring is secured at one end to the bat 21 and at the other to the body 20.

As mentioned hitherto the arm 26 is hinged to the body as at 27 by means of the hinge plate 50 which is fastened by screws, nails or any other means to the body, and which accommodates a hinge pin 51 carried by the arm 26. By the aforementioned description it is seen that the bat 21 is caused to swing on the bar 30 when the arm 26 is moved or oscillated, and to simulate the movement of a bat, when operated by a baseball player, recourse to the springs 47 and 49 is had which act as oscillation dampers 80 amplifiers for the said bat.

To move the arm 26, the following mechanism may be employed, it being understood that any other type of mechanism may be resorted to, to move the said arm without departing from the spirit of my invention: a motor 55 may be arranged at the base of the player's figure of the device, preferably at its rear, as shown in Fig. 3, or on the back of this figure, as shown in Fig. 4. On the shaft of this motor is arranged a gear 56 meshing with another gear 57, the latter gear being mounted in any convenient manner on a shaft 58 journaled in a bearing or bearings 59. The gear 57 mounts a cam 61 on which rides a trolley 62 held at the end of a rod 63 by means of a bifurcated member 64. The trolley 62 is journaled on the shaft 65 carried by the bifurcated member 64, and to this shaft 65 is secured a spring 66 the opposite end of which may be secured to any convenient place as at 67. This spring 66 urges the trolley 62 to continually ride the cam 61. At the upper end of rod 63 is mounted a slotted member 70 in which is pivoted the lower portion of an actuator 71 which is pivotally mounted on the body 20 by means of a shaft 72 and brackets 73. The upper end of the actuator 71 mounts a pair of rollers 75 normally bearing against a plate 76 carried by the arm 26 at its under surface. When the motor rotates, its rotation is imparted to the gear 57 and to the cam 61, and as the trolley 62 rides the cam 61, the rod 63 is forced into a reciprocating movement, the periods of which vary with the various center to contour distances presented by the cam 61 at the point where the trolley 62 is located, as it rotates. The reciprocation of rod 63 causes the actuator 71 to oscillate on the shaft 72 and to move the arm 26 which is held pressed against the rollers 75 by the spring 49. The bat 21 occupies its foremost position when the trolley 62 rides in the cam groove or depression 80, and occupies the innermost position, or the position against the buffer plate 40, when the trolley rides on the cam face projection 81. The bat swings from its foremost to its rearmost position once during

every revolution of the cam 61 and the depressions and projections presented by the cam 61, besides the depression 80 and the projection 81, are for the purpose of giving the bat a number of intermediate oscillations to simulate the oscillations of a bat manipulated by a baseball player while waiting a pitched ball. Hence through the medium of the motor 55, the cam 61, the trolley 62, the actuator 71, the arm 26 and the various connections employed between the arm 26 and the bat 21, and of the pivot connection of the bat 21 on the rod 30, the bat is given a movement simulating the movement of a bat manipulated by a player, and thereby gives to the players, using the device, an added interest in hitting the bat, since it is made more difficult to be hit by the intermediate oscillations between its foremost and rearmost position.

Having described the illustrated mechanism or the operation of the bat, I shall now describe the indicating mechanism through which the hits scored by the pitched balls against the bat are indicated. The bat adjacent its hitting end is provided with a longitudinally extending bore or recess 85 and a plurality of through bores 86 intersecting the longitudinal bore 85. There are preferably four bores 86 in each of which is slidably arranged a plug 87 each formed with a head 88 and a tapering point 89 at the opposite end. These plugs, for the purpose of identification, have been marked, as shown in Fig. 11, as, home base plug, third base plug, second base plug, first base plug; the home base plug being arranged at the upper or outer end and the first base plug at the inner end. Each of these plugs may preferably be formed between its ends with an annular groove 90, in which normally lays the point 91 of a pin 92 actuated by a spring 93 urging said pin 92 toward the plug. The construction just described is not absolutely necessary because the operation of the plugs can efficiently take place without the aid of the pins 92, especially if the plugs fit rather snugly into the bores 86. When a ball or article pitched against the bat hits any one of these base plugs, the base plug hit is forced inwardly and the tapered point thereof closes against the plates 95 which plates are part of the electrical circuit to be hereafter more specifically described. At the rear of the bat or at the part where the plates 95 are secured is arranged a buffer 98 which abuts against the buffer plate 40 every time the bat swings fully rearwardly so as to prevent the plates 95 from hitting against the said buffer plate 40. Whenever any one of the base plugs has been pushed inwardly by a pitched ball or otherwise, the point 99 carried by each plug moves beyond the plane of the face of the buffer 98 and upon the

bat approaching the buffer plate 40 the plug or plugs driven inwardly are forced outwardly and held in the outward position by the pins 91 which, being urged in one direction by the springs 93, enter into the groove 90 and hold the plugs in place until pressed or hit by the pitched ball. From the above description it is seen that the base plugs 87 are normally held as shown in Figs. 8 and 10, and when hit by a pitched ball they are forced inwardly as shown in Fig. 8, and stay in that position until the bat swings rearwardly and hits against the buffer plate 40, when the points 99 encountering the buffer plate 40, force their respective base plugs outwardly into their normal position.

Reference is now had to the electrical circuit and more particularly to Figs. 2 and 12. At the rear of the bat, as heretofore mentioned, are secured a plurality of plates or electrical contacts 95 which comprise bus plates 100 and 101, first bus plate 102, second bus plate 103, third bus plate 104 and home plate 105. All of these plates 90 are separated and isolated from each other and all are formed with grooves 106 in which enter the tapered portions of the base plugs when hit and forced inwardly. There is a source of electrical energy 110, one side of which is connected through wires 111, 112 and 113 to the bus plates 100 and 101. The opposite side of this source of electrical energy is connected to a common conductor through a wire 115. This common conductor is connected to one terminal of each lamp 117. The outer terminals of the lamps 117 are connected in the following manner: The lamp indicating first base on the diamond is connected, through wire 121, to the plate 102; the lamp indicating second base is connected, through wire 122, to plate 103; the lamp indicating third base is connected, through wire 123, to plate 104; and the lamp indicating the home base is connected, through wire 120, to plate 105. As the plates 102, 103, 104, and 105 are normally disconnected from the bus plates 100 and 101, the current from the source of electrical energy 110 is normally prevented from flowing through the lamps indicating the respective bases, but whenever any one of the base plugs is forced inwardly the respective bus plate is connected to the adjacent lamp plate and current is permitted to flow through the lamp until the bat swings fully rearwardly and the plug closing the circuit is returned to its normal position as shown in either Figs. 8 or 10. As an illustration, assuming that a pitched ball hits the home plate plug, the same establishes a connection between the bus plate 101 and the plate 105 and thus the current is caused to flow from the source of electrical energy 110, through the wires 111, 113, bus plate 101, 120

home base plug, plate 105 and wire 120, through the filament of lamp 117, indicating the home base, through the common conductor 114, wire 115, back to the source of electrical energy 110.

5 The indicating board 124, representing the baseball diamond on which the lamps are mounted, may be mounted on a stand 125 at any distance from the figure of the player. 10 In Fig. 1, where this diamond is shown, the bat is not shown connected with the lamps 117 on the indicating board so as to avoid complications; but the diagrammatical connection is well illustrated in Fig. 2 wherein 15 the upper portion of the bat and its electrical plates are shown connected with the lamps on the bases of the diamonds.

10 The wires connecting the battery with the plates 105 and the lamp plates with the 20 lamps 117 may be arranged in a group or in a cable along the rear of the bat and along the rear of the Fig. 20 and from thence connected to the lamps on the diamond. This particular arrangement of the 25 wires is not necessary to be shown, for any one skilled in electrical wiring can understand the arrangement described, or resort to one of his own.

20 In Fig. 4 is shown a modified form of the invention wherein the motor 55 is mounted on brackets 130 on the rear of the player's figure 20. The shaft 131 of the motor may be journaled at its outer end in bearing 132. The shaft mounts a worm 133 which meshes 35 with a worm gear 134 carrying a cam 135 shaped more or less the same as the cam 61 in Fig. 3. The shaft mounting the worm gear 134 in the cam 135 may have a bearing on a bracket 135 secured on the body 20. 40 The trolley 137, the slotted member 138 and the actuator 139 may be identical in construction to the similar members described heretofore in connection with the mechanism shown in Fig. 3; but the rod 140 which 45 connects the bifurcated member 141 with the slotted member 138 is, of course, shorter than the rod 63, shown in Fig. 3. The construction shown in Fig. 4 and just briefly described has for an object that of making 50 the device more compact and that of driving the gear 134 by means of a worm instead of a pinion gear, so as to permit the use of a high speed motor.

55 The device may be installed in any place and the players desiring to use it are given a certain fixed distance from which they may pitch their balls against the bat which, being in continuous movement, is rather hard to be hit, and therefore the device is 60 not only amusing but also a fine medium to train players in the art of pitching balls.

65 Although the device has been principally designed for manually projecting articles against it, the same may be used in connection with a fixed projecting mechanism,

which mechanism may project articles against the bat instead of pitching the same by hand. The device may also be manufactured in a miniature size for family amusement, and, if desired, a projecting mechanism, on the principle of a spring rifle, may be associated therewith for projecting miniature balls against the bat.

70 I would state in conclusion that while the illustrated examples constitute a practical embodiment of my invention, I do not limit myself strictly to the exact details herein illustrated, since, manifestly, the same can be considerably varied without in the least departing from the spirit of the invention 75 as defined in the appended claims.

Having described my invention, what I claim is:

1. An amusement device comprising a human figure provided with means against which articles may be pitched, means to indicate the accuracy with which the said articles have been pitched against the said first mentioned means, said last mentioned means comprising an electric circuit, an indicating device disposed adjacent to the said human figure, a sliding element closing said circuit when hit by the said pitched article or articles, and spring means for holding the said sliding elements to hold the same 90 against accidental movement.

2. An amusement device comprising a human figure, moving means pivoted on the said figure against which articles may be projected while the said means are moving, 100 an electric circuit, an element on the said moving means for closing the said electric circuit, and spring means for holding the said element against accidental movement.

3. An amusement device comprising a human figure, swinging means pivoted to the said figure, indicating means to indicate the hits scored against the said swinging means comprising an electric circuit, a circuit closer, and spring means for holding the 110 said circuit closer against accidental movement.

4. An amusement device comprising a support representing a human figure, a baseball bat pivoted on said support, and a plurality of indicating means actuators carried by said bat; together with indicating means actuated by said actuators.

5. An amusement device comprising a support, moving means pivoted on said support, a slidable member formed with a tapering end carried by said moving means and indicating means actuated by said slidable member.

6. An amusement device comprising a support, moving means pivoted on said support, a slidable plug formed with a tapered end carried by said moving means, and an electrical circuit adapted to be closed by the tapered end of said plug.

7. An amusement device comprising a support, moving means pivoted on said support, a plug formed with a head at one end and a tapered portion at the other, and an electrical circuit adapted to be closed by said plug when hit and moved by a projected article.
8. An amusement device comprising a support, a pivoted member mounted thereon, a plurality of slidable members carried by said pivoted member, and means carried by said member and associated with said slid- 10 able members for closing an electrical circuit when said slidable member is moved.
15. 9. An amusement device comprising a support, a pivoted member mounted thereon, said pivoted member being formed with a plurality of substantial transversely ex- 80 tendsing bores, a slidable member arranged in each bore, and means also carried by said pivoted member adapted to cooperate with said slidable members to close an electrical circuit upon the movement in one direction of either of said slidable members.
20. 10. An amusement device comprising a support, a bar secured to said support, a member pivoted to said bar, a moving arm, means connecting the moving arm with the pivoted member, and a spring for urging 90 the moving arm and the pivoted member in one direction.
11. An amusement device comprising a support, a bar secured to said support, a member pivoted to said bar, a moving arm, 35 means connecting the moving arm with the pivoted member so as to transmit the motion of the moving arm to the pivoted member, and means carried by said support for limiting the rearward movement of said pivoted member.
40. 12. An amusement device comprising a body, a member pivoted thereto, a moving arm connected with said pivoted member to swing the same, a spring to urge the arm and the pivoted member in one direction, and a second spring positioned between the arm and the pivoted member and acting as a cushion between the two.
50. 13. An amusement device comprising a support, a bar secured thereto, a baseball bat pivoted to said bar, a moving arm, a stub carried by said moving arm and engaging said bat, and a spring interposed between the said bat and said support for urging 100 the bat and the arm in the one direction.
55. 14. An amusement device comprising a support, a bar secured thereto, a baseball bat pivoted to said bar, a moving arm, a stub carried by said moving arm and engaging said bat, a spring interposed between the said bat and said support for urging the bat and the arm in the one direction, and a spring surrounding said stub interposed between the arm and the bat and acting as a cushion between the two.
15. An amusement device comprising a support, a bar secured thereto, a baseball bat pivoted to said bar, a moving arm, a stub carried by said moving arm and engaging said bat, a spring interposed between the 110 said bat and said support for urging the bat and the arm in the one direction, together with a second spring interposed between the bat and the arm for cushioning the two.
16. An amusement device comprising a support, a bracket pivoted to said support, a baseball bat held in said bracket, means for swinging said bat on said support, said bat being formed with a plurality of through bores, a slidable member held in each bore, an electrical circuit, a plurality of electrical terminals connected in said circuit and adapted to be connected with respect to each other by said slidable members, and indicating means placed in said circuit 120 by said slidable members.
17. An amusement device comprising a swing bat, an electrical circuit, a plurality of indicating means connected with said circuit, a plurality of slidable plugs carried by said bat, and means on the bat to close the circuit to the indicating means when either of said slidable plugs should move off their normal position.
18. An amusement device comprising a movable baseball bat, an electrical circuit, indicating means and a miniature baseball diamond connected with said circuit, and means passing through bat for closing the circuit to any one of said indicating means 130 on the miniature diamond.
19. An amusement device comprising a movable baseball bat, an electrical circuit, indicating means and a miniature baseball diamond connected with said circuit, means passing through bat for closing the circuit to any one of said indicating means on the miniature diamond.
20. An amusement device comprising a swingable bat, a miniature diamond provided with an indicating means at each base of the diamond, and means passing through bat for actuating any one of said indicating 140 means on the miniature diamond.
21. An amusement device comprising a swingable bat, a miniature diamond provided with an indicating means at each base of the diamond, an electrical circuit for said indicating means, and means passing through bat for closing the electrical circuit to any one of said indicating means on the miniature diamond.
22. An amusement device comprising a movable baseball bat, an electrical circuit, a plurality of indicating means in said circuit, and means passing through bat for closing said electrical circuit on any of said indicating means.

23. An amusement device comprising a movable baseball bat or the like, a miniature diamond, an indicating device on each base of the diamond, an electrical circuit therefor, a plurality of electrical terminals on the bat connected in said circuit and with said indicating means, and means for closing the electrical circuit to any one of said indicating means.
- 10 24. An amusement device comprising a pivoted baseball bat, an electrical circuit, a plurality of insulated electrical terminals arranged on said bat, and a plurality of switch means for establishing the circuit through said terminals and thereby actuating an indicator.
- 15 25. In combination with a swinging baseball bat, an electrical circuit, and means on the bat for closing said electrical circuit and actuating an electrical indicating means.
- 20 26. In combination with a movable baseball bat, an electrical circuit, indicating means in said circuit, and means on the bat for closing said electrical circuit on to said indicating means.
- 25 27. In combination with the movable baseball bat, an electrical circuit, a plurality of indicating means arranged on a miniature baseball diamond, said indicating means being connected in said electrical circuit, and a plurality of switching means on the bat for closing said electrical circuit to either of said indicating means.
- 30 28. In combination with a movable bat, an electrical circuit, a plurality of indicating means arranged on a miniature baseball diamond connected within said electrical circuit, a plurality of slidable plugs carried by said bat, and electrical terminals on the bat connected in said electrical circuit for establishing a flow of current through said indicating means when either of said plugs is moved from its normal position.
- 35 29. In combination with a baseball bat pivoted on a support, an electrical circuit, a plurality of electrical terminals mounted on the bat and connected with said circuit, a plurality of indicating means arranged away from said bat but electrically connected with said terminals thereon and with said circuit, and a plurality of slidable means adapted to electrically connect said indicating means with said terminals when moved in one direction.
- 40 30. An amusement device comprising a support, a baseball bat pivoted to said support, a hinged arm connected with said bat, a cam arrangement for moving said arm on its hinge and thence said bat, and motor means for moving said cam arrangement.
- 45 31. An amusement device comprising a support, a baseball bat pivoted to said support, a moving arm connected with said bat, a cam arrangement for moving said arm and thence said bat, and motor means for moving said cam arrangement, together with an electrical circuit and an electrical indicating means associated with said bat to indicate when said bat has been hit by a projected article, part of said electrical circuit being carried by said bat.
- 50 32. An amusement device comprising a support, a motor, a cam arrangement actuated by said motor, a pivoted arm, means between said pivoted arm and said cam arrangement for transmitting the motion of said cam arrangement to said arm, and a bat connected with said arm to be moved thereby.
- 55 33. An amusement device comprising a support, a motor, a cam arrangement actuated by said motor, a pivoted arm, means between said pivoted arm and said cam arrangement for transmitting the motion of said cam arrangement to said arm, a bat connected with said arm to be moved thereby, electrical indicating means and contact means on said bat for closing and opening said electrical circuit.
- 60 34. An amusement device comprising a support, a baseball bat pivoted to said support, said bat being provided with a plurality of transversely extending bores, a slidable member arranged in each bore, electrical contacts carried by said bat and adapted to be shunted with respect to each other by either of said slidable members, an electrical circuit connected with said terminals, a plurality of indicating means in said circuit adapted to be closed in a circuit by said slidable members, a moving arm connected with said baseball bat to move the same, and motor means for intermittently actuating said arm.
- 65 35. In testimony whereof, I have signed my name to this specification this 20th day of October, 1923.
- 70 MARTIN VERBEYST,
